UNITED STATES PATENT OFFICE.

WILLIAM F. LIEBLER, OF NEW YORK, N. Y.

NAIL SET.

Application filed January 16, 1923. Serial No. 612,932.

To all whom it may concern:

Be it known that I, WILLIAM F. LIEBLER, a citizen of the United States, and a resident of the county of Bronx, city and State of 5 New York, have invented certain new and useful Improvements in Nail Sets, of which the following is a specification.

My invention relates to improvements in devices for setting nails and is particularly 10 directed to such devices as are employed in the setting of nails in laying parquet floors and the like where it is necessary to sink the nail below the surface of the wood.

One of the objects of my invention is the 15 provision of a device wherein the nail set proper or point may be readily removed from its holder and replaced when it becomes worn out or broken.

Another object of my invention is the 20 provision of a device of the character indicated provided with a portion for engaging the work when the nail is set to impart to the wood the final blow desirable to properly seat the wood thereby eliminating 25 the necessity of an extra blow for the purpose.

A further object of my invention is the 30 provision of a structure whereby the work, that is the nail being set and the set itself, is visible at all times.

Further objects of my invention will be manifest from the following description and the accompanying drawing, in which—

Fig. 1 is an elevational view of a device 35 embodying my invention;

Fig. 2 is a longitudinal sectional view of the same; and

Fig. 3 shows a modification.

Referring to the drawings in detail,—1
40 designates a holder which is preferably knurled and is provided with a longitudinal hole 2 at one end thereof adapted to receive a point 3 which is the member or device which actually engages the nail to be set during the setting operation. This nail setting point, it will be noted, is provided with an annular groove 4 which when the point is in position in the holder is directly opposite a threaded opening 5 in the holder. 45
50 This opening is adapted to receive a set screw 6 which screw enters the groove 4 on the nail point 3 and tends to hold the point securely against its seat in the bottom of the hole 2 at all times to impart the desired 55 rigidity to the tool as a whole.

It will be noted that the point 3 by means

of this arrangement will be held rigidly in the holder when in use with the same effect as though the structure were a unitary one and that the point may be readily removed 60 for repair or replacement when broken or worn out.

The holder 1 is cut away at one side to provide a bevelled portion 7 through the surface of which extends the nail setting point 3, whereby the point and the nail being set are always in view and not obstructed by the holder which inconvenience is commonly encountered in devices of this 65 nature.

The lower end 8 of the holder presents a flat face or surface and is purposely so constructed to provide means for engaging the floor or other work to give it the final blow which is desirable to properly seat the work 70 as the nail is driven home. This feature is very advantageous inasmuch as at present it is necessary to give the work an extra blow with the hammer after the nail is set for this purpose. In the present device this 75 extra blow, of course, is eliminated.

The nail setting point 3 passes through the surface of the bevelled portion 7 and the flat end 8, the point passing preferably through the juncture of 7 and 8. The point 80 3 is elongated and is preferably cylindrical so as to avoid making the hole in the work above the nail any larger than is necessary and also to prevent the point from becoming caught in the opening above the nail, as is sometimes the case with the ordinary nail sets as now constructed. The removal of the nail set from the head of the nail is also facilitated by the engagement of the end 8 of the holder with the wood being nailed down which causes the 85 holder to rebound.

In Fig. 3 I have shown a modified form of the nail setting point. The front of this figure is designated 9 and the tip is fluted 90 as designated at 10 for the purpose of making or providing an irregular or roughened hole in the wood above the head of the nail for receiving putty or other filler, the irregularity of the hole thus formed tending 95 to hold the filler in place.

It is to be understood that I do not wish to be limited to the precise construction as shown and described as the same may be varied within the purview of my invention. 100 105 110

I claim:

1. A nail set comprising a holder having

a bevelled portion adjacent its lower end and a nail setting point extending through the bevelled surface of said bevelled portion and removably secured in said holder.

5. A nail set comprising a holder having a flat lower end and a cutaway portion at one side to provide a bevelled portion adjoining said flat end, and a nail setting point extending through the juncture of said bevelled portion and flat end.

10. 3. A nail set comprising a holder having a flat bevelled face adjoining a flat end face, and a removable nail setting point extending through the juncture of said faces.

4. A nail set comprising a holder, one 15 end of which is provided with a flat face and one side of which is bevelled to meet or join the flat end, said holder also being provided with a longitudinal cavity at the juncture of said flat face and bevelled portion, a nail setting point provided with an annular groove intermediate its ends, and means co-operating with said groove for retaining said point in place in the cavity in said holder.

20 25 This specification signed this 6th day of January, 1923.

WILLIAM F. LIEBLER.
